Patented Apr. 21, 1936
A device for a fuel injection pump to facilitate
the injection of fuel into the engine at the
time when the fuel is most effective. It is
designed to be used in conjunction with a
pump which has a cam to operate the piston
and a barrel piston which has a cam to operate
the nozzle. The device is designed to be used
with a pump which has a cam to operate the piston
and a barrel piston which has a cam to operate
the nozzle.

FUEL INJECTION PUMP

Frederick L. Parsons, Reading, Mass., assignor to
Benjamin Howe, trustee, Reading, Mass.

Application August 6, 1934, Serial No. 738,577

5 Claims. (Cl. 103—37)

This invention relates to fuel injection pumps for use with Diesel engines and the like, and the object is to provide a simple and rugged construction of pump whereby a desired quantity of fuel may be injected at a desired time into the engine cylinder.

The nature of my invention and the advantages resultant from its use will be well understood by those skilled in the art by reference to the following description of the illustrative embodiment thereof shown by way of example in the accompanying drawing which shows the pump in longitudinal section with the parts at the beginning of the injection stroke.

Referring to the drawing, the operating parts of the pump may be organized in connection with a suitable base or body 5 having an intake passage 7 adapted to communicate with a fuel supply and discharge passage 9, herein shown as connected by means of a pipe 11 with an injection nozzle 13 carrying a check valve 15 normally held closed by a spring 17 which provides a determined resistance to the injection of fuel into the cylinder (not shown). Herein I have shown the body 5 as supporting a suitable liner 19 having a cylindrical bore in which works a piston hereinafter to be referred to and provided with a passage 21 forming a continuation of the intake passage 7 and opening to the inner cylindrical bore of the liner and with a passage 23 opening from that bore and extending to the discharge passage 9. The junction of the passages in the body and the liner is made at the meeting face 25 of the opposed annular shoulders of the body and the liner which are held pressed together by the threaded collar 27. This arrangement, as will be apparent in the drawing, facilitates the formation of the passages referred to. The body and the liner also provide a passage 29 from intake 7 to the inner bore of the liner for a purpose hereinafter to be referred to, this passage opening at a distance from the opening of the passage 21.

Working in the liner I provide a piston 31 in the form of a cylindrical sleeve closed at the lower end by the plugs 33 and 35. The piston thus takes the form of a hollow cylinder with an open inner end, and for the sake of brevity I shall hereinafter refer to such a construction as a barrel piston. This piston is reciprocated in the liner by power and herein a spring 37 interposed between the overhanging flange at the upper end of collar 27 and a bearing ring 39 supported at the lower end of the piston tends to thrust it downwardly and holds it in cooperating relation with a cam 41 on a shaft 43. The cam in the example

illustrated is in the form of a simple eccentric which is desirable notably for engines operating at relatively high speeds. Herein the cam acts against the base of a cup-like member 45 telescoping within collar 27 and cooperating therewith to enclose the spring and which aids in guiding the parts axially.

Telescoping within the barrel piston 31 is a counter-piston 47, the lower face of this piston and the opposed face of the barrel piston formed by plug 33 defining between them a working chamber to receive a charge of liquid to be injected on each cycle. Opening from this chamber laterally through the circumferential walls of the barrel piston are intake and discharge ports 49 and 51 respectively which preferably, for reasons which will appear, take the form of circumferentially disposed slots rectangular in outline. Since herein the openings of the intake and discharge passages 21 and 23 to the bore of the liner are vertically spaced, the ports 49 and 51 are disposed opposite each other and at the outer extremity of the stroke of the barrel piston, as shown in the drawing, port 49 is in communication with passage 21, whereas on or about the other extreme of the stroke the discharge port 51 is presented to the discharge passage 23. The counter-piston 47 is normally urged inwardly (downwardly in the figure) by a light spring 55 interposed between the upper end of the piston 30 and an abutment screw 57 by means of which the tension of the spring may be adjusted. Inward movement of the piston under the influence of this spring is limited, however, by contact of the collar 59 with adjustable stop arms 61 mounted on a transverse pin or shaft 63 and adjustably supported at their other ends by the eccentrics 65 on a shaft 67 which may be manually or automatically rotated as desired. This adjustment limiting the inward movement of the counter-piston 47 toward the bottom of the barrel piston in the position of the latter shown in the drawing determines the size of the working chamber and thus the volume of the charge of fuel handled by the pump on each cycle.

Supported by a shoulder in the casing 5 is a cup-like member 69 pressed downwardly by a heavy spring 71 of substantially greater effective force than the spring 17 of the nozzle, which spring is interposed between the bottom of the cup and the screw cap 73. In the outward or upward movement of the counter-piston when pressed in the manner herein more fully described by the mechanically driven barrel piston acting through an interposed column of liquid 55

in the working chamber of the pump, the collar 59 during the latter portion of the stroke of the counter-piston makes contact with cup 69 and compresses the spring 71.

- 5 I have now described more or less arbitrarily the exemplary mechanical construction illustrated in the drawing. I will now describe the operation of the pump shown. Assuming the parts to be in the position shown in the drawing, 10 the barrel piston is in its extreme outward position on the low point of the cam 41 and the counter-piston is supported in the position shown by the stop arms 61 against the stress of spring 65 forming a working chamber between the opposed faces of the pistons, which we may suppose 15 filled with liquid supplied through intake passage 21 and port 49. As the barrel piston 31 now rises, port 49 is first carried out of alignment with passage 21, thus trapping in the chamber a 20 charge of liquid. As the barrel piston continues to rise, it moves outwardly before it the counter-piston 41, the former acting on the latter through the incompressible column of fluid trapped within 25 in the working chamber. The initial portion of this movement is, in the construction shown, an easy one against the light spring 55, thus assuring a positive cut-off action at port 49. The counter-piston 41 continues to move outwardly or upwardly as the cam rotates and collar 59 30 compresses spring 71 placing the tension of the latter on the imprisoned column of fluid. Toward the end of the stroke the port 51 is brought into alignment with the passage 23, spring 71 expands 35 powerfully and quickly, overcoming the tension of spring 17 on the check valve 15 of the injection nozzle, and quickly and powerfully injects the charge of fuel through the check valve and into the cylinder. The counter-piston, no longer supported by the fluid column, descends within 40 the barrel piston.

Preferably I provide the counter-piston with a passage 75 opening from the lower face thereof laterally to the side and the wall of the barrel piston with a port 77, the arrangement of the 45 parts being such that as the injecting action under the stress of the spring 71 just described takes place the port 77 is in alignment with the passage 29 leading to the intake, and when the counter-piston has descended into contact with 50 or to a predetermined clearance from the bottom of the barrel piston the passage 75 aligns with the port 77. It will be noted that the alignment of the various passages depends on the position of the barrel piston and the fixed determined 55 throw of the cam 41 thereon. At the end of the injection stroke, therefore, the pressure is relieved regardless of speed or load, permitting the valve 15 to snap shut. There are thus no pressure waves ensuing upon the cut-off which might 60 tend to secondary discharges, there is no residual pressure in the high pressure line which might tend to vary the quantity discharged and there is no leakage at the injection valve 15.

On the opposite stroke the barrel piston descends, closing the discharge, and counter-piston 65 41 may follow it until checked by the stop arms 61. The barrel piston, however, continues to descend forming a vacuum and, when at about the end of the stroke the parts resume the position 70 of the drawing, the port 49 in alignment with passage 21 provides for drawing a new charge of fuel into the working chamber.

The injection of the fuel under the pressure of spring 71 provides a uniform but controllable 75 injection pressure at all speeds, avoiding over-

straining of the mechanism, and a rapid injection at low speeds to insure atomization. It permits in many instances of the use of a simple eccentric as here shown or other low acceleration cam with consequent low structural loading on the pump parts. The valve action provided for by the ports 49 and 51 is particularly simple and permits the use of a rectangular port giving rapid operation with large effective areas and avoiding clogging. The intake and delivery are positively timed while there is no restriction to flow caused by spring loading and no bouncing which might lead to pressure fluctuation.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:—

1. A fuel injection pump for delivering fuel to an engine against a determined resistance comprising a casing having intake and discharge passages, a power-reciprocated barrel piston working therein having a bore and provided with lateral ports opening to said bore adapted to register respectively with said passages adjacent the extremes of the piston stroke, a counter-piston telescoping within the bore of said barrel piston to define a liquid-receiving chamber therein, means providing an adjustably variable clearance between the opposed faces of the pistons in the outward position of the barrel piston, a resilient resistance relatively strong as compared with said determined resistance opposing outward movement of said counter-piston during the latter portion of its outward stroke under drive of said barrel piston through a charge of liquid in the chamber, and means in said counter-piston placing said chamber in communication with the intake side of the pump substantially at the inward limit of movement of the counter-piston under said strong resistance after the inward movement of the barrel piston has placed the chamber in communication with the discharge passage.

2. A fuel injection pump for delivering fuel to an engine against a determined resistance comprising a casing having intake and discharge passages, a power-reciprocated barrel piston working therein with lateral ports adapted to register respectively with said passages adjacent the extremes of the piston stroke, a counter-piston telescoping in said barrel piston to define a liquid-receiving chamber therein, means providing an adjustably variable clearance between the opposed faces of the pistons in the outward position of the barrel piston, a resilient resistance relatively strong as compared with said determined resistance opposing outward movement of said counter-piston during the latter portion of its outward stroke under drive of said barrel piston through a charge of liquid in the chamber, a passage leading from the inner end of the counter-piston, and means comprising a port in the barrel piston and a passage in the casing to open said counter-piston passage to the intake side of the pump substantially at the inward limit of movement of the counter-piston under said strong resistance after the inward movement of the barrel piston has placed the chamber in communication with the discharge passage.

3. A fuel injection pump for delivering fuel to

an engine against a determined resistance comprising a casing, a power-reciprocated piston working therein, a counter-piston, a spring relatively strong as compared with said resistance 5 against which spring said counter-piston is moved during the latter part of its outward travel by force of the power reciprocated piston exerted through an interposed column of fluid, port means providing for discharge of said column located 10 to be opened independently of the position of the counter-piston, and a venting passage for the space between the pistons opened to the intake side of the pump consequentially to completion of the movement of said counter-piston under its 15 spring consequent on opening of said port means.

4. A fuel injection pump comprising a casing having intake and discharge passages, a power reciprocated barrel piston working therein having an intake port adapted to register with said intake passage at the outward position of the piston, a spring-supported counter-piston telescoping in said barrel piston to provide a fluid-receiving chamber between them, means providing an adjustably variable clearance between 20 the opposed faces of the pistons in the outward position of the barrel piston, the barrel piston having a lateral port adapted to cooperate with said discharge passage at a definite time in its stroke independently of the position of the 25 counter-piston, and means providing a connec- 30

tion from said chamber through the counter-piston to the intake side of the pump opened when said piston faces approximate one another at the conclusion of the discharge.

5. A fuel injection pump for delivering fuel to 5 an engine against a determined resistance comprising a casing having intake and discharge passages, a power-reciprocated barrel piston working therein having a bore and provided with lateral ports opening to said bore adapted to 10 register respectively with said passages adjacent the extremes of the piston stroke, a counter-piston telescoping within the bore of said barrel piston to define a liquid-receiving chamber therein, means to determine the volume of liquid 15 to be delivered from between said pistons on their ejection movement, a resilient resistance relatively strong as compared with said determined resistance opposing outward movement of said counter-piston during the latter portion of its 20 outward stroke under drive of said barrel piston through a charge of liquid in the chamber, and means in said counter-piston placing said chamber in communication with the intake side of the pump substantially at the inward limit of move- 25 ment of the counter-piston under said strong resistance after the inward movement of the barrel piston has placed the chamber in communication with the discharge passage.
